PORTABLE CRIMPING TOOL FOR ELECTRICAL CONNECTIONS

George Ustin, Verona, N.J., assignor to Buchanan Electrical Products Corporation, Hillside, N.J., a corporation of New Jersey

Filed Jan. 12, 1960, Ser. No. 59,026

Term of patent 14 years

(Cl. D54—14)

FIG. 1

Des. 191,635

PAGE 2

FIG. 2

FIG. 3

Des. 191,635

PAGE 3

FIG. 4

FIG. 5

FIG. 6

FIGURE 1 is a side elevational view of a Portable Crimping Tool for Electrical Connections, showing my new design;

FIGURE 2 is a bottom view as seen from the right of FIGURE 1;

FIGURE 3 is a top view as seen from the left of FIGURE 1;

FIGURE 4 is a side elevational view thereof opposite the side shown in FIGURE 1;

FIGURE 5 is an end view looking down on FIGURE 1; and

FIGURE 6 is an end view looking up on FIGURE 1. The dominant features of my design reside in the portions shown in full lines.

I claim:

The ornamental design for a portable crimping tool for electrical connections, as shown and described.
